TOY JAIL PLAYHOUSE

Larry G. Clark, 5532 Hollister Drive,
Indianapolis, Ind. 46224

Filed Aug. 21, 1970, Ser. No. 24,622

Term of patent 14 years

Int. Cl. D21—01

U.S. Cl. D34—15

Fig.1

Fig.2.

Fig.3.

Fig.5.

Fig.4

FIG. 1 is a front elevational view of a toy jail playhouse showing my new design.

FIG. 2 is a left side view thereof.

FIG. 3 is a top plan view thereof.

FIG. 4 is a right side view thereof.

FIG. 5 is a rear view thereof.

The bottom is without ornamentation.

I claim:

The ornamental design for a toy jail playhouse, as shown and described.
